US00D840232S

(12) **United States Design Patent** (10) **Patent No.:** **US D840,232 S**
Sill et al. (45) **Date of Patent:** **** Feb. 12, 2019**

(54) **COMPARTMENTED CARTON INSERT**(71) Applicant: **Inno-Pak, LLC**, Delaware, OH (US)(72) Inventors: **Jonathan D. Sill**, Powell, OH (US);
Steven A. Mayer, Indianapolis, IN (US)(73) Assignee: **Inno-Pak, LLC**, Delaware, OH (US)(**) Term: **15 Years**(21) Appl. No.: **29/582,402**(22) Filed: **Oct. 27, 2016**(51) LOC (11) Cl. **09-07**

(52) U.S. Cl.

USPC ..... **D9/456**(58) **Field of Classification Search**

USPC D3/20, 200, 201, 272, 273, 295, 304, D3/309–315, 318, 319, 901, 903, 904; D6/515–525, 532, 536, 672, 677, 683, D6/704, 707.15; D7/323, 339, 347, 354, D7/355, 356, 359, 360, 362, 392.1, 396.1, D7/412, 500, 505, 549, 550.1, 552.1, D7/552.2, 553.1, 553.2, 553.4, 553.5, D7/553.6, 553.7, 554.1, 555, 600.1, 601, D7/602, 614, 615; D9/414, 415, 416, D9/418, 428–430, 500, 630, 682, 686, D9/688, 690, 692, 703, 737, 738, 740, D9/744, 755–762, 904, 434, 455, 456; D12/163, 197, 415, 425; D19/1, 27, 78, D19/102, 103, 106, 107; D21/502, 524, D21/525, 532, 832; D24/127, 128, 216, D24/224, 227, 228, 229, 230; D28/61, D28/73, 76; D32/55, 58; D30/121, 129, D30/130, 131

CLAIM

The ornamental design for a compartmented carton insert, as shown and described.

DESCRIPTION

FIG. 1 is a perspective view of a first embodiment of the compartmented carton insert showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof showing the compartmented carton insert inserted in a carton;

FIG. 9 is a perspective view of a second embodiment of the compartmented carton insert;

FIG. 10 is a front view thereof;

FIG. 11 is a rear view thereof;

FIG. 12 is a left side view thereof;

FIG. 13 is a right side view thereof;

FIG. 14 is a top plan view thereof;

FIG. 15 is a bottom plan view thereof;

FIG. 16 is another perspective view thereof showing the compartmented carton insert inserted in a carton;

FIG. 17 is a perspective view of a third embodiment of the compartmented carton insert;

FIG. 18 is a front view thereof;

FIG. 19 is a rear view thereof;

FIG. 20 is a left side view thereof;
FIG. 21 is a right side view thereof;
FIG. 22 is a top plan view thereof;
FIG. 23 is a bottom plan view thereof;
FIG. 24 is another perspective view thereof showing the compartmented carton insert inserted in a carton;
FIG. 25 is a perspective view of a fourth embodiment of the compartmented carton insert;
FIG. 26 is a front view thereof;
FIG. 27 is a rear view thereof;
FIG. 28 is a left side view thereof;
FIG. 29 is a right side view thereof;
FIG. 30 is a top plan view thereof;
FIG. 31 is a bottom plan view thereof; and,
FIG. 32 is another perspective view thereof showing the compartmented carton insert inserted in a carton.
The broken lines are shown for the purpose of illustrating environmental subject matter of a carton and form no part of the claimed design.
